Primary Examiner — Sheryl Lane*Assistant Examiner* — Stacey L Hopkins(74) *Attorney, Agent, or Firm* — Alston & Bird LLP(57) **CLAIM**

The ornamental design for a flashlight, as shown and described.

DESCRIPTION

FIG. 1 is a bottom front perspective view of a flashlight according to my new design.

FIG. 2 is a top rear perspective view of the flashlight of FIG. 1.

FIG. 3 is a front view of the flashlight of FIG. 1.

FIG. 4 is a back view of the flashlight of FIG. 1.

FIG. 5 is a left side view of the flashlight of FIG. 1.

FIG. 6 is a right side view of the flashlight of FIG. 1.

FIG. 7 is a top view of the flashlight of FIG. 1; and,

FIG. 8 is a bottom view of the flashlight of FIG. 1.

Throughout the drawings the broken lines depict portions of the flashlight that form no part of the claimed design.

1 Claim, 7 Drawing Sheets
